UNIVERSAL SHEAVE BLOCK

Edward G. Albright, Jr., Lynwood, Calif.

Application September 29, 1952, Serial No. 312,036

3 Claims. (Cl. 254—194)

1

This invention relates to a sheave block which is mounted on the bed of a truck for the purpose of guiding a cable which extends to a power driven drum on the truck.

An object of my invention is to provide a universal sheave block which will adjust itself to permit the cable to pull in a wide variety of angles from the sheave block itself. Furthermore, the sheave block can be variously mounted in a socket which is attached to the bed of the truck.

Another object of my invention is to provide a novel universal sheave block in which the cable can be easily threaded onto the sheave by lifting a latch which is pivotally mounted on the body of the sheave block.

Another feature of my invention resides in the novel mounting of the trunnion which projects from the sheave plates, this trunnion being journaled in the housing, thus permitting the sheave to rotate through an angle of 360°.

Another feature of my invention resides in the novel means of mounting the trunnion in the body of the sheave block assembly and in which the trunnion is tubular, so as to permit the cable to pass lengthwise through the trunnion.

Other objects, advantages and features of invention may appear from the accompanying drawing, the subjoined detailed description and the appended claims.

In the drawing:

Figure 1 is a diagrammatic plan view of a truck with my sheave block mounted thereon.

Figure 2 is a side elevation of the sheave block assembly with parts broken away to show interior construction.

Figure 3 is a top plan view of the sheave block assembly.

Figure 4 is a front elevation of the same with parts broken away to show interior construction.

Figure 5 is a perspective view of the sheave plates and trunnion.

Referring more particularly to the drawing, the numeral 1 indicates a truck body upon which a power driven winch or drum 2 is mounted. The cable 3 is wound on the drum 2 and extends over the sheave assembly 4, as will be further described.

The universal sheave block assembly 4 is an improvement over Patent No. 1,955,942. In order that the sheave block assembly 4 may be securely mounted on the truck body 1, I provide a socket 5 which is securely bolted, or otherwise fixedly attached to the bed 1 of the truck. The

2

socket 5 is provided with a hole therein, and this hole is preferably square, or some other convenient angular shape. A sheave body 7 is formed with a depending shank 8 and this shank is square or angular in cross-section to conform to the shape of the hole 6. Thus the shank 8 is held in a fixed position in the hole 6.

A pin 9 extends through the socket 5 and the shank 8 to hold this shank within the body and to prevent it from moving upwardly under strain when the cable is pulling from an upward direction. The body 7 is formed with a horizontal bore 10 and this bore acts as a bearing for the trunnion 11. The trunnion 11 projects from a pair of side plates 12—13 and is preferably an integral part of these side plates. The trunnion 11 is formed of tubular stock and is held fixedly in the bearing 10 by means of a flange 14 which is welded or otherwise fixedly secured to the trunnion 11 after the trunnion has been positioned in the bearing 10 of the body 7.

A slot 15 in the top of the trunnion 11 permits the cable 3 to drop into the trunnion when it is threaded onto the sheave. A pulley 16 is journaled between the side plates 12—13 on the pin 17. A latch 18 is pivotally mounted on the body 7 by means of the pins 19 and 20 and this latch closes the slot 21 which is formed in the top of the body 7 and through which the cable 3 passes when it is being threaded onto the pulley 16.

It will be evident from the foregoing description, that the pulley 16 can rotate within the body 7 on its trunnion 11 and the pulley will align itself with the cable 3, depending upon the direction in which the cable is pulling. The trunnion 11 permits rotation around a horizontal axis, as will be evident. The latch 18 may be provided with a lug 22 which projects into the slot 21, thus more effectively holding the cable 3 in engagement with the pulley 16, especially when the cable is pulling almost horizontally.

In operation the universal sheave block is mounted on the rear end of the truck body 1 by bolting or otherwise securing the socket 5 on the back of the body. The shank 8 is now dropped into the socket 5 and thereafter the cable 3 is threaded over the pulley 16 by first lifting the latch 18 so as to expose the slot 21, and also the opening 15 in the top of the trunnion 11. The cable then drops through the slot 11 through the opening 15 in the trunnion and is then threaded over the pulley 16, all of which is easily and quickly accomplished. Thereafter the pulley 16

will automatically align itself with the direction of pull of the cable 3 by rotation of the trunnion 11 in its bearing 10 and about a substantially horizontal line.

Having described my invention, I claim:

1. A universal sheave block comprising a socket having a vertically extending hole therein, a sheave body, a shank depending from said body and fitting in said hole, said body having a substantially horizontal bore therein, said body having a slot therein opening into said bore, and latch means on the body extending over and closing said slot, a pulley, a pair of spaced side plates, a pin mounted in the side plates, said pulley being journaled on said pin, and a trunnion extending from the side plates and journaled in said bore.

2. A universal sheave block comprising a socket having a vertically extending hole therein, a sheave body, a shank depending from said body and fitting in said hole, said body having a substantially horizontal bore therein, a pulley, a pair of spaced side plates, a pin mounted in the side plates, said pulley being journaled on said pin, and a trunnion extending from the side 25

plates and journaled in said bore, said trunnion being tubular in form and said trunnion having a slot therein alignable with said slot in the body.

3. A universal sheave block comprising a socket having a vertically extending hole therein, a sheave body, a shank depending from said body and fitting in said hole, said body having a substantially horizontal bore therein, said body having a slot therein opening into said bore, and latch means on the body extending over and closing said slot, a pulley, a pair of spaced side plates, a pin mounted in the side plates, said pulley being journaled on said pin, and a trunnion extending from the side plates and journaled in said bore, said trunnion being tubular in form and said trunnion having a slot therein and alignable with said slot in the body.

EDWARD G. ALBRIGHT, JR.
